FRANK C. MASON, OF LOS ANGELES, CALIFORNIA.

CLUTCH-LOCK FOR MOTOR-VEHICLES.

1,295,343.

Specification of Letters Patent. Patented Feb. 25, 1919.

Application filed December 29, 1917. Serial No. 209,580.

To all whom it may concern:

Be it known that I, FRANK C. MASON, a citizen of the United States, residing at Los Angeles, in the county of Los Angeles and State of California, have invented a new and useful Clutch-Lock for Motor-Vehicles, of which the following is a specification.

This invention relates to means for locking the clutch of an automobile or other motor vehicle, so that the machine cannot be started or cannot be moved under its own power, thereby preventing theft of the machine.

The main object of the present invention is to provide means for this purpose which will constitute an effective lock and at the same time will not bring excessive strain on the locking means when the locking device is released.

The accompanying drawings illustrate an embodiment of my invention and referring thereto:

Figure 1 is a side elevation of the invention as applied to a clutch control lever or pedal of an automobile.

Fig. 2 is an elevation from the opposite side from Fig. 1, with the cover plate removed.

Fig. 3 is a section on line 3—3 in Fig. 2.

Fig. 4 is a side elevation of a modified form of locking bar and detent.

The device comprises a suitable frame or casing 1, a barrel or cylinder 2, rotatively mounted in said casing 1, a locking bar 3, movable through said barrel and a key-operated lock carried by said barrel and adapted to control the movement of said locking bar.

The frame 1 may be mounted on the lower part of the dash-board indicated at 5 and may be provided with two annular standards 6 formed with cylindrical openings 7, in which the cylinder 2 is rotatively mounted, said cylinder being provided with end plates 8 and 9 secured thereto and engaging shoulders 10 on said annular standards for retaining the said cylinder from longitudinal displacement. Cylinder 2 is provided with

holes 12 in its cylindrical wall, through which the locking bar 3 works, said locking bar being pivotally connected at 14 to the pedal 15, connected in any suitable or other manner to the clutch controlling means 16.

The locking bar 3 is provided with one or more notches forming shoulders 18 adapt-

ed to be engaged by a dog or detent 19 pivoted at 20 on a lug 21 attached to the inside of barrel 2, and a spring 23 engages said dog or detent 19 so as to tend to hold 60 or force it into engagement with the one or other of the shoulders 18 in the locking bar, and a spring 25 engages said dog or detent so as to tend to throw it out of such engagement, said spring 25 being weaker 35 than the spring 23 so that its action is overcome by that of spring 23 when the latter is operative. The key-operated lock 27, of any suitable construction, and provided with a key operated member 28 having a keyhole 70 slot 28' for receiving a suitable key, is mounted in the cylinder 2 and is provided with a bolt 29 controlled by operation of the key-operated member 28, said bolt carrying a pin or projection 30 adapted to engage the 75 spring 23 to move it away from the dog or detent 19 and allow said dog or detent to be released from the locking bar by the operation of spring 25. Cylinder 2 may be retained in position by a screw 26 in frame 30 1, engaging in a slot 26' in said cylinder, so as to prevent endwise displacement of the cylinder within said frame, while permitting rotative movement of the cylinder, within the limits determined by the length 85 of said slot.

In the normal operation of the clutch control pedal 15, for placing the engine in and out of operative relation to the driving gear of the machine, the locking bar 3 slides forward and backward through the holes 12 in cylinder 2, the bolt 29 of the key operated lock being protracted so that the pin 30 thereon engages with the spring 23 to release it from the dog or detent 19 and the latter 95 being then held out of engagement with the notches 18 in the bar 3 by the spring 25. The device therefore in no way interferes with the usual operation of the clutch pedal. When the operator desires to leave the vehicle protected he operates the lock by means of a suitable key, inserted in the means 28, so as to retract the bolt and permit the spring 23 to press the dog or detent 19 into engagement with the bar 3. The operator may then 100 press the pedal forward so as to throw the clutch into released position and in this movement the bar 3 is moved forward so as to bring one of the shoulders 18 into engagement with the detent 19, which then holds 105 the clutch mechanism in released position, preventing unauthorized driving of the ve-

hicle. On unlocking the locking device by means of the proper key, operating the lock to protract the bolt 29 and cause the pin 30 to press the spring 28 back, and on then 5 pressing forward the pedal 15 so as to throw bar 3 forward and relieve the detent 19 from the pressure of the shoulder 18, said detent is moved by its spring 25 out of position for engagement with the shoulders 18 so that the 10 clutch means is freely movable to position for control of the machine in running. It will be noted that the bar 3 is provided with inclined faces 38 forward of the respective shoulders 18, so that the bar can move freely 15 in one direction, say for throwing in clutch into released position. By reversing the directions of the shoulders and inclined faces on the clutch controlling bar 3, the device may be adapted to lock the clutch into 20 operative position, so that a person in order to start the car, would have to crank the machine while connected to the driving gear, and in some cases it may be preferred to depend on this manner of control for preventing 25 theft, as it is almost impossible to crank the engine under such conditions. Or by making the shoulders square faced, and providing said shoulders in proper position on the bar as shown at 40 in Fig. 3 and forming 30 the detent indicated at 41, and a square faced tooth for engaging said shoulders, the bar may be held from movement in either direction, and the clutch may be locked in operative or inoperative position, as may be desired. This form of detent and shoulder is 35 also adapted to Ford machines, where it is desired to lock the clutch in "neutral" position.

In the operation of the device as above described, the clutch controlling bar 3 slides in the holes 12 in cylinder 2 which serve to 40 guide the same, and said cylinder turns in its bearings 7 in frame 1, so as to provide for

the slight swinging movement of said bar due to its pivotal connection with the pedal. 45

What I claim is:

1. A locking device for motor vehicle clutches, comprising a clutch controlling member connected to and movable with, the clutch controlling mechanism, and provided 50 with shoulder means, a detent movable into and out of engagement with said shoulder means for holding the clutch controlling member in fixed position, a detent-operating spring for holding said detent in position 5 for engaging said shoulder means, and key controlled means for engaging said detent-operating spring to render it inoperative, said detent being provided with means for moving it out of position for engagement 6 with the shoulder means when the key controlled means is moved to position for rendering the detent-operating spring inoperative, and the clutch controlling member is moved so as to momentarily relieve the pressure of the shoulder means on said detent. 6

2. A locking device for motor vehicle clutches, comprising a movable clutch controlling bar, having a notch formed with a shoulder, a frame, a cylinder mounted to turn in said frame and provided with guide means through which said bar is slideable, a detent mounted in said cylinder, a spring for pressing said detent into engagement with said notch in the clutch controlling bar, a key controlled lock mounted on said cylinder and having a bolt provided with means for engaging said spring to remove it from said detent, and a spring for engaging said detent to remove it from said notch on such removal of the first named spring.

In testimony whereof I have hereunto subscribed my name this 18th day of December, 1917.

FRANK C. MASON.
